SEMI-AUTOMATIC PACKAGE WRAPPING
MACHINE

Franklin M. Willbrandt, Battle Creek, Mich., assignor to
Battle Creek Packaging Machines, Incorporated, Battle
Creek, Mich.

Filed Apr. 7, 1961, Ser. No. 101,543
9 Claims. (Cl. 53—206)

This invention relates to improvements in semi-automatic package wrapping machine. The principal objects of this invention are:

First, to provide a machine having both manually and automatically actuated parts which will facilitate the operation of wrapping a wrapper sheet of transparent material such as cellophane over and around food packages and in particular flat paper trays containing meat and produce.

Second, to provide a produce packaging machine which will effectively form second, third and fourth folds across the underside of a package and retain the folds in place while the package is passed in a sliding motion along a single flat surface across a heat sealing element to seal the folds.

Third, to provide a package wrapping and sealing machine in which the operator can perform all of the wrapping and sealing operations in a single plane and in which part of the folding operation on the wrapper is accomplished by mechanism leaving the operator's hands free to manipulate the package.

Fourth, to provide a package wrapping machine which will draw a wrapper sheet downwardly over the top and side of a package and pull the sheet snugly over the package while folding the end of the sheet in a bottom fold along the bottom surface of the package.

Fifth, to provide a simple and inexpensive wrapping mechanism to facilitate and speed the manual wrapping of packages of various sizes.

Other objects and advantages of the invention will be apparent from a consideration of the following description and claims.

The drawings, of which there are two sheets, illustrate a highly practical form of the wrapping mechanism.

FIG. 1 is a side elevational view of the wrapping mechanism.

FIG. 2 is a fragmentary enlarged plan view of the mechanism with a portion of the top broken away to illustrate operating connections therebelow.

FIG. 3 is a fragmentary vertical cross sectional view taken along the plane of the line 3—3 in FIG. 2.

FIG. 4 is a schematic or diagrammatic view showing the several stages or steps in the progressive wrapping of a package with the machine of the invention. The view shows the package and wrapper in plan views.

FIG. 5 is a conventional or schematic view of the wrapping steps shown in side elevation with corresponding steps projected from FIG. 4. The several successive steps in FIGS. 4 and 5 are identified by the letters A through H as corresponding sections of FIGS. 4 and 5.

FIG. 6 is an enlarged fragmentary vertical cross sectional view through the wrapper sheet retaining roller and showing a wrapper in operative position relative to a package being wrapped.

The wrapping mechanism is built into a table having

2

a flat top 1 supported upon suitable legs 2. Shelves 3 are adapted to support different sized boxes 4 of commercially available sheets of wrapping material such as heat sealable cellophane cut in diamond shape. An extension bar 5 slidably in the top surface of the table at the rear or left end thereof supports one of the larger boxes at approximately the same position on the table. It will be understood that the operator selects the size of wrapper sheet to wrap the particular packages being handled. 5 Intermediate of its ends the table top 1 has a transversely extending slot or trough 6 formed therein with a flat cross bar 61 at its bottom. Immediately to the rear or left of the groove 6 are two holes 7 for stop lugs 8. Near the front or right edge of the table is a transverse slot 9 for a heated sealing plate 10. Openings 11 at each end of the groove 6 pass vertically reciprocable support rods or flat bars 12 that support a transverse gripper bar in the form of a roller 13 as will be described. The trough 6 is deep enough so that the roller is substantially 10 completely received in the groove to bear frictionally upon a single layer or thickness of a wrapper sheet 14 wrapped around a package 15 and pressed against the bar 61 as will be described. (See FIG. 6.)

Bracket plates 16 projecting from the right legs support the right end of the table top and have upright guideways 17 on their inner sides which retain and guide the support bars 12. The plates 16 also support bearings 18 for the cross shaft 19 which has handles 20 on each end at the outer sides of the table. A rock shaft 21 is supported by bearings 22 rearwardly of the cross shaft. The rock shaft 21 has angled crank arms 23 at each end projecting toward the support bars 12 and depending links 24 connect the crank arms to the lower end of the support bars with pivots at 25 and 26 respectively. The 15 cross shaft 19 has crank arms 27 that are connected to intermediate positions of the cranks 23 by reversely C-shaped links 28. Pivots for the links 28 appear at 20 and 29.

From the foregoing it will be apparent that with the 25 handles 20 in the lowered full line position illustrated, the cranks 27 will be raised raising the C-links 28, and through them the cranks 23, links 24 and support bars 12 to elevate the roller 13 well above the table 1. The elevation of the roller is such as to permit a sheet of 30 wrapping material 14 to be passed over the largest package to be wrapped such as a chicken or rib roast of beef and easily passed underneath the raised roller as will be described. The lowered positions of the parts indicated by the dotted lines and reference numerals with suffix A 35 position the roller in the trough 6.

A short rock shaft 31 supported by bearings 32 to the right of the roller trough 6 has crank arms 33 supporting the heated seal plate 10. An oppositely extending arm or beam 34 supports the stop lugs 8. The shaft 31 and arms 33 and beam 34 are oscillated by a depending crank 35 connected by a link 36 with a short crank 37 on the rock shaft 21. This causes the stops 8 to move up and the heater 10 to go down when the roller 13 is raised.

60 The reverse C-shape of the links 28 places the pivots 29 and 30 on the rear side of the cross shaft 19 when the roller is raised so that the weight of the roller and connected support bars 12 which is substantial, tends to rotate the cranks 27 counterclockwise locking the links

23 against shaft 19. The linkage is thus self locking in the raised position of the roller.

In order to leave the operator's hands free to manipulate the package and wrapper, means are provided for lowering the roller other than by manipulation of the handles 20. Short crank arms 38 on the cross shaft are disposed in slots formed in the ends of push bars 39. The push bars extend rearwardly to cranks 40 pivoted on the underside of the table. Spring biased push rods 41 extending through the sides of the table and provided with buttons 42 on their outer ends are provided with pins 43 engaged in notches 44 in the cranks. Bias springs for the bars are shown at 45. By bumping either button 42 with his hip the operator can push the cranks 38 and cross shaft 19 past center so that roller 13 falls by gravity into the trough 6 to rest on the bar 61 or a sheet of wrapping material interposed therebetween.

The cycle of operation of the machine is as follows:

The operator lowers a handle 20 at either side of the machine thus raising the roller 13. A sheet 14 of wrapping material is laid flat on the table behind the roller and a package 15 to be wrapped is placed over the front corner of the wrapper as shown in FIGS. 4A and 5A and against the stop lugs 8 as shown in FIG. 6. The roller 13 being raised out of the way, the operator swings or loops the trailing edge of the wrapper forwardly over the package and across the trough 6 as shown in FIGS. 4B and 5B. Note that the operator's hand need not project under the roller to do this. The operator then bumps the knob 42 and the roller 13 falls by gravity pressing the over folded end of the wrapper into the trough 6 as shown in FIGS. 5C and 6. The roller exerts a yieldable tension on the wrapper 14 as the operator next slides the package forwardly over the roller 13. This folds the over folded edge of the wrapper snugly over the package and back under the bottom of the package and forms a first bottom fold and overlaps as shown at 46 in FIGS. 4D and 5D and a simple sliding motion passes the overlap forwardly and backwardly over the sealing plate 10 sealing the first overlap.

The package, now with a tubular wrapper may be left open at the ends but is often returned over the still lowered roller to the rear side of the stop lugs 8 and the roller is raised as in FIGS. 4E and 5E. Relowering the roller and advancing the package again forms a second or end overlap 47 which is sealed on the hot plate in the same manner as the first underlap. (See FIGS. 4F and 5F.) The package is again reversed as in FIGS. 4G and 5G and the process repeated to form the finished package with all four sides of the wrapper lapped under the package and sealed to each as in FIGS. 4H and 5H.

At no time is it necessary to lift the package off of the table and after the initial positioning of the flat sheet and package and the swinging of the sheet over the package as in FIG. 5B, the entire operation is a sequence of sliding operations back and forth over the roller and the heated seal plate. The finished package may be disposed of to any suitable receiving rack or table.

What is claimed as new is:

1. A semi-automatic package wrapping machine comprising

a flat top table having a wrapper supply supporting area at one end and a heated sealer bar reciprocable from underneath the table to the surface thereof at the other end of the table,

a transverse trough formed in said table between said supporting area and said bar,

a package supporting area on said table between said wrapper supply area and said trough,

a package stop vertically reciprocable through said table between said package area and said trough and closely adjacent the trough,

a pair of vertically reciprocable uprights positioned to project above said table at each end of said trough,

a transverse roller freely rotatably supported between

75

the upper ends of said uprights and arranged to rest against the bottom of said trough and below the surface of said table in the lowered position of said uprights,

5 manually operable means for reciprocating said uprights including guideways for the lower ends of the uprights mounted below said table,

levers fixedly pivoted below said table and having links pivotally connected to the lower ends of said uprights,

a cross shaft journalled below said table and having an operating handle on each end,

cranks on said cross shaft having second links on their swinging ends pivotally connected to intermediate portions of said levers,

said cranks and second links being arranged to move to overcentering position relative to said cross shaft in the elevated position of said uprights,

a transversely reciprocable spring loaded plunger projecting from each side of said table,

linkage connected between said plungers and said cross shaft to push said cranks back past center relative to said cross shaft when one of said plungers is pushed,

a rocker beam mounted below said table and supporting said sealer bar and said package stop,

and another crank connected to oscillate with said levers and connected to said beam to raise said sealer bar to the level of said table when said roller is lowered and raise said package stop when said roller is raised.

2. A semi-automatic package wrapping machine comprising

a flat top table having a wrapper supply supporting area at one end and a heated sealer bar reciprocable from underneath the table to the surface thereof at the other end of the table,

a transverse trough formed in said table between said supporting area and said bar,

a package supporting area on said table between said wrapper supply area and said trough,

a package stop vertically reciprocable through said table between said package area and said trough,

a pair of vertically reciprocable uprights positioned to project above said table at each end of said trough,

a transverse roller freely rotatably supported between the upper ends of said uprights and arranged to rest against the bottom of said trough in the lowered position of said uprights,

manually operable means for reciprocating said uprights including guideways for the lower ends of the uprights mounted below said table,

levers fixedly pivoted below said table and having links pivotally connected to the lower ends of said uprights,

a cross shaft journalled below said table and having an operating handle on one end,

cranks on said cross shaft having second links on their swinging ends pivotally connected to intermediate portions of said levers,

said cranks and second links being arranged to move to over-centering position relative to said cross shaft in the elevated position of said uprights,

a transversely reciprocable spring loaded plunger projecting from one side of said table,

linkage connected between said plunger and said cross shaft to push said cranks back past center relative to said cross shaft when said plunger is pushed,

a rocker beam mounted below said table and supporting said sealer bar and said package stop,

and means actuated by said cross shaft connected to said beam to raise said sealer bar to the level of said table when said roller is lowered and raise said package stop when said roller is raised.

3. A semi-automatic package wrapping machine comprising

a flat top table having a wrapper supply supporting area at one end and a heated sealer bar reciprocable from underneath the table to the surface thereof at the other end of the table, 5

a transverse trough formed in said table between said supporting area and said bar, 5

a package stop vertically reciprocable through said table between said package area and said trough, 10

a pair of vertically reciprocable uprights positioned to project above said table at each end of said trough, 10

a transverse roller freely rotatably supported between the upper ends of said uprights and arranged to rest against the bottom of said trough in the lowered position of said uprights, 15

manually operable means for reciprocating said uprights including 15

levers fixedly pivoted below said table and having links pivotally connected to the lower ends of said uprights, 20

a cross shaft journaled below said table and having an operating handle on one end, 20

cranks on said cross shaft having second links on their swinging ends pivotally connected to intermediate portions of said levers, 25

said cranks and second links being arranged to move to over-centering self locking position relative to said cross shaft in the elevated position of said uprights, 25

a rocker beam mounted below said table and supporting said sealer bar and said package stop, 30

and means actuated by said cross shaft connected to said beam to raise said sealer bar to the level of said table when said roller is lowered and raise said package stop when said roller is raised. 30

4. A semi-automatic package wrapping machine comprising 35

a flat top table having a wrapper supply supporting area at one end and a heated sealer bar reciprocable from underneath the table to the surface thereof at the other end of the table, 40

a transverse trough formed in said table between said supporting area and said bar, 40

a pair of vertically reciprocable uprights positioned to project above said table at each end of said trough, 45

a transverse roller freely rotatably supported between the upper ends of said uprights and arranged to rest against the bottom of said trough in the lowered position of said uprights, 45

manually operable means for reciprocating said uprights including 50

levers fixedly pivoted below said table and having links pivotally connected to the lower ends of said uprights, 55

a cross shaft journaled below said table and having an operating handle on one end, 55

cranks on said cross shaft having second links on their swinging ends pivotally connected to intermediate portions of said levers, 60

said cranks and second links being arranged to move to over-centering self locking position relative to said cross shaft in the elevated position of said uprights, 60

a rocker beam mounted below said table and supporting said sealer bar, 65

and means operated by said cross shaft connected to said beam to raise said sealer bar to the level of said table when said roller is lowered. 65

5. A package wrapping table having a groove formed in the 70

surface thereof with a package receiving area on one side of the groove and a wrapper sealing area with a retractable heating sealing plate therein on the other side of the groove, 70

means spaced below the top of said table and extending transversely under said groove to form a bottom for the groove, 75

a gripper bar rollingly receivable in said groove with portions engaged with the means forming the bottom surface of the groove at points spaced therealong over a substantial portion of the central part of said groove and with the top of the bar substantially flush with the adjacent surface of the table, 70

supports connected to the ends of said bar and rollingly supporting said bar, 70

and means including a manually operable handle mounted on said table and connected to said supports to lift said bar out of said groove to a position spaced substantially above said table to permit a wrapper sheet to be passed over a package on said receiving area to a position of the sheet overlying said groove. 70

6. A package wrapping table having a groove formed in the 75

surface thereof with a package receiving area on one side of the groove and a wrapper sealing area with a heated sealing plate therein on the other side of the groove, 75

means spaced below the top of said table and extending transversely under said groove to form a bottom for the groove, 80

a gripper bar receivable in said groove with portions engaged with the means forming the bottom surface of the groove at points spaced therealong over a substantial portion of the central part of said groove and with the top of the bar substantially flush with the adjacent surface of the table, 80

supports connected to the ends of said bar, 80

and means including a manually operable handle mounted on said table and connected to said support to lift said bar out of said groove to a position spaced substantially above said table to permit a wrapper sheet to be passed over a package on said receiving area to a position of the sheet overlying said groove. 80

7. A package wrapping table having a groove formed in the 85

surface thereof with a package receiving area on one side of the groove and a wrapper sealing area with a retractable heated sealing plate therein on the other side of the groove, 85

means spaced below the top of said table and extending transversely under said groove to form a bottom for the groove, 85

a gripper bar rollingly receivable in said groove with portions engaged with the means forming the bottom surface of the groove at points spaced therealong over a substantial portion of the central part of said groove and with the top of the bar substantially flush with the adjacent surface of the table, 90

supports connected to the ends of said bar and rollingly supporting said bar, 90

and means including a manually operable handle mounted on said table and connected to said supports to lift said bar out of said groove to a position spaced substantially above said table to permit a wrapper sheet to be passed over a package on said receiving area to a position of the sheet overlying said groove. 90

said manually operable means being further connected to said sealing plate to raise said plate to the surface of said table when said bar is lowered. 90

8. A package wrapping table having a groove formed in the 95

surface thereof with a package receiving area on one side of the groove and a wrapper sealing area with a heated sealing plate therein on the other side of the groove, 95

means spaced below the top of said table and extending transversely under said groove to form a bottom for the groove, 95

a gripper bar receivable in said groove with portions engaged with the means forming the bottom surface

7
of the groove at points spaced therealong over a substantial portion of the central part of said groove and with the top of the bar substantially flush with the adjacent surface of the table, supports connected to the ends of said bar, and manually operable means mounted on said table and connected to said supports to lift said bar out of said groove to an elevation spaced substantially above said table.

9. A package wrapping table having a groove formed 10 in the surface thereof with a package receiving area on one side of the groove and a wrapper sealing area with a heated sealing plate therein on the other side of the groove, means spaced below the top of said table and extending 15

transversely under said groove to form a bottom for the groove,
a gripper bar receivable in said groove with portions engaged with the means forming the bottom surface of the groove at points spaced therealong over a substantial portion of the central part of said groove and with the top of the bar substantially flush with the adjacent surface of the table, supports connected to the ends of said bar, and means mounted on said table and connected to said supports to lift said bar out of said groove to an elevation spaced substantially above said table.
